SEAT CUSHION FOR A WHEELCHAIR

Carl Henrik Elgebrandt, Farsta, Sweden, assignor to
Camp Scandinavia AB, Helsingborg, Sweden

Filed Nov. 2, 1973, Ser. No. 412,432

Term of patent 14 years

Int. Cl. D6—09

U.S. Cl. D6—201

FIG. 1

FIG. 2

FIG. 3

FIG. 1 is a front, top and right side perspective view of a seat cushion for a wheelchair showing my new design; FIG. 2 is a rear, bottom and right side perspective view; and

FIG. 3 is a front elevational view on an enlarged scale.

I claim:

The ornamental design for a seat cushion for a wheelchair, substantially as shown.
